FRANK A. DOWLER, OF LAWRENCE, KANSAS.

AUTOMOBILE TIRE-PUMP.

1,137,956.

Specification of Letters Patent.

Patented May 4, 1915.

Application filed July 19, 1912. Serial No. 710,370.

To all whom it may concern:

Be it known that I, FRANK A. DOWLER, a citizen of the United States, residing at Lawrence, in the county of Douglas and State of Kansas, have invented certain new and useful Improvements in Automobile Tire-Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to tire pumps, and has for its principal object to provide a combination lifting jack and pump whereby a driving wheel of an automobile may be supported above the ground and turned by the motor in the car to operate the pump and furnish air for filling tires. In accomplishing this object I have provided the improved details of structure hereinafter described and illustrated in the accompanying drawings, wherein:—

Figure I is a perspective view of the driving wheels of an automobile, showing the application of my improved tire pump thereto. Fig. II is a vertical section of the pump. Fig. III is a perspective view of the piston. Fig. IV is a longitudinal section of same. Fig. V is a sectional view of the lower end of the pump.

Referring more in detail to the parts:— 1 designates a lifting jack comprising a base 2 and toothed post 3. Slidably mounted on the post is a lifting member 4, having a catch pawl 5, a handle 6, and a spring pressed handle pawl 6', all of which may be of ordinary construction, and need not be described in detail, as the jack, *per se*, forms no part of my present invention.

Revolutely mounted in a journal 7, at the top of the post 4, is a sleeve 8, having end flanges 9 for keeping it in the journal and having a central channel 10 adapted for receiving the outer end of a driving wheel hub, a collar 11 being projected inwardly from the sleeve near its outer end to fit over the cap of the hub to which the pump is applied, the collar 11 being preferably hexagonal or square to fit over the usual hexagonal or square hub cap.

Projecting laterally from the outer flange

9 is an arm 12, having a stub shaft 12' thereon, and revolvably mounted on said stub shaft is the rod 13 of an air pressure pump 14, which is, in turn, pivotally mounted upon a stud 15 that projects laterally from the lower end of the lifting member of the jack.

Rod 13 is slidably projected through the cap 16 of pump 12, and connects with a piston 17 comprising heads 18—18', the former of which has studs 19 rigidly fixed to and projecting from its face opposite that to which the pitman is connected, while the latter is slidably mounted on the studs, the outward travel of head 18' being limited by the heads 19' of the studs 19.

Each of the pistons is provided with the usual rings 20 and with non-registering apertures 21 and 22, so that when the piston is reciprocated in the pump barrel, and the heads moved into and out of contact with each other, the apertures 21 and 22 will be opened and closed, as will presently be described.

Near the lower end of the pump barrel is a laterally and upwardly opening channel 24, which terminates in a nipple 27 that opens from the side of the chamber and has a flexible tube 26 connected therewith and adapted for connection with a tire, which it is desired to inflate.

In using the device the jack is applied to the wheel of an automobile by projecting the jack collar 8 over the outer end of the hub so that the hub cap will seat in the collar 11. The wheel is then jacked from the ground, the tube 26 connected with one of the tires on the car, or the tire of another car, and the motor started, the wheel to which the pump is connected being turned through the differential gearing indicated by the casing 21, so that the locking of the hub cap on sleeve 11 and frictional contact of the hub and the sleeve in the journal 7 will actuate the pump rod.

As the pump rod descends, head 18', being retarded by friction against the side of the pump barrel, remains stationary until the head 18 meets it and carries it downward, the meeting of the heads closing the apertures 21 and 22 to force air through the valve 25 and through tube 26 into the tire. When the rod is lifted, head 18' remains stationary until engaged by the heads 19' of studs 19, at which time the upper head 18 is 110

spaced therefrom and the two heads are carried upwardly with their inner faces spaced apart, so that air may be admitted therethrough to the pump barrel from the top 5 of the pump.

In order that the car may be raised without binding the bearings of the device, I have provided the base with a crown so that a slight change in position of the jack will 10 still leave the parts in equilibrium.

Having thus described my invention, what I claim as new therein and desire to secure by Letters-Patent, is:

1. A tire pump for automobiles, comprising 15 a base member, a movable member adjustably supported on said base member, a sleeve revolvably mounted in said movable member and adapted to receive the hub of a wheel to support the weight of the automobile and induce frictional contact between 20 the wheel hub and sleeve, a pump pivotally mounted on said movable member, and a

crank arm on said sleeve for actuating said pump.

2. A tire pump for automobiles comprising 25 a base member, a movable member adjustably mounted on said base member, a sleeve revolvably mounted in said movable member and adapted to receive the hub of a wheel to support the weight of the automobile and induce frictional contact between 30 the wheel hub and sleeve, an inwardly directed flange having an irregular, apertured portion for operatively engaging the hub cap of the wheel, a pump pivotally mounted 35 on said movable member, and a crank arm on said sleeve operatively connected with said pump.

In testimony whereof I affix my signature in presence of two witnesses.

FRANK A. DOWLER.
